FREE-PISTON AIR-COMPRESSORS

Evelyn Stewart Lansdowne Beale, Wraysbury, England, assignor to Alan Muntz & Company Limited, Hounslow, England

Application August 30, 1955, Serial No. 531,537

Claims priority, application Great Britain
September 9, 1954

4 Claims. (Cl. 230—23)

The present invention relates to free-piston air-compressors, that is to say air-compressors in which an engine piston working in an engine cylinder has coupled thereto a compressor piston working in a compressor cylinder, energy stored in the compressor cylinder by the compression of air during each working stroke of the engine piston serving to drive the engine piston on its compression stroke, and the compressor cylinder being in communication with a compressed air reservoir through one or more delivery valves.

When such a compressor is started with the air in the reservoir at atmospheric pressure, it is necessary to block the delivery valve or valves in order to maintain sufficient pressure in the compressor cylinder to return the engine piston on its compression stroke. Various means have been used or proposed for this purpose, certain of which are, for example, described in British patent specifications Nos. 373,488 and 391,676. These and most other known blocking means are designed to operate with plate-type delivery valves in which the amount of lift of the plate is relatively small, for example about 2 mm., and the required movement of the blocking means between its operative and inoperative condition is correspondingly small.

Another type of delivery valve, sometimes known as a "streamline"-type valve, has come into use and has advantages over the older plate-type valve. In the streamline-type valve a number of thin steel laminae are clamped along one edge and the laminae are arranged to flex between a closed position in which they bear upon suitable seatings and an open position in which they are supported by stop plates. The planes of the laminae are approximately parallel to the direction of air flow. Examples of such valves are disclosed in British patent specifications Nos. 580,171 and 706,354.

With streamline valves the area to be blocked is the whole outlet area at the face of the valve and in order to avoid unduly restricting the outlet when unblocked a much larger movement of the blocking means between the blocked and fully un-blocked positions is required, for instance about 16 mm. In addition, the force which has to be exerted when blocking is greater than with plate-type valves because of the greater area to be blocked.

Another difficulty to be overcome is that if the un-blocking pressure is too low there is a danger of the compressor stopping directly after un-blocking, for lack of enough return-energy in the compressor cylinder. On the other hand it must be arranged that blocking cannot occur under any normal running conditions of the compressor.

The present invention has for its object to provide improved blocking means, suitable for use with streamline-type valves, in which the force exerted during blocking and the extent of movement can be relatively large, in which the transition from the blocked to the fully un-blocked condition takes place with a relatively small change in pressure in the reservoir, and in which the change from the fully un-blocked to the blocked condi-

2

tion can be arranged to take place at a substantially lower reservoir pressure than the change from the blocked to the fully un-blocked condition.

According to the present invention, there is provided a free-piston air-compressor having one or more delivery valves controlling the delivery of air from a compressor cylinder to a reservoir, means for blocking the one or more delivery valves by the application of a suitable force to the blocking means, and automatically-operating blocking control means for un-blocking the valves by removal of the said force, the blocking control means comprising two pistons of different diameters each working in a cylinder, the pistons being coupled together and in their blocking position applying, or permitting the application of, the said force to the blocking means and in their un-blocking position removing, or permitting the removal of, the said force, spring means urging the pistons toward their blocking position, the front face of the larger piston being subjected to the pressure of the reservoir, pressure on this face tending to move the pistons toward their un-blocking position, the rear face of one of the pistons being in communication with the atmosphere, and means whereby when the pistons are in their blocking position the rear face of the other of the pistons is subjected to the pressure of the reservoir and whereby in response to a predetermined increase in the reservoir pressure the pistons move into their unblocking position in which the rear face of the said other piston is subjected to atmospheric pressure.

Preferably the rear face of the larger piston is in communication with the atmosphere, the rear face of the smaller piston being subjected to the reservoir pressure when in the blocking position and to atmospheric pressure when in the un-blocking position.

The invention will be described by way of example with reference to the accompanying drawings in which

Fig. 1 is a view in sectional elevation of part of a free-piston air-compressor embodying the invention,

Fig. 2 is a view in section on the line 2—2 of Fig. 1 and

Fig. 3 is a diagrammatic representation of another embodiment of the invention.

Referring to Figs. 1 and 2, a compressor cylinder 10 has an end cover plate 11 secured by studs 12, the cover plate 11 having water-cooling passages 13 and two delivery valves 14 and 15 which are of the streamline type already referred to. The valves are secured in apertures in the cover plate 11 by means of a clamping plate 16 and studs 17. These valves control the delivery of air from the cylinder 10 to reservoirs which are not shown but are connected to the delivery passages 18 formed in the compressor casing 19.

For the purpose of blocking the delivery valves 14 and 15 there are provided two blocking plates 24 and 25 which are slidable perpendicular to the paper in Fig. 2 and are guided by elongated studs 26 passing through apertures in the plates 24 and 25. A spring (not shown) surrounds each stud 26 and is located between the blocking plate and the clamping plate 16 thus tending to urge the blocking plates away from the face of the valve and thus into the un-blocked position.

The two blocking plates 24 and 25 are yoked together by a bridge piece 27. The blocking plates are rockably mounted upon the bridge piece 27 and a short spring (not shown) is provided under each nut 28 which screws on to a stud threaded into the blocking plate. The rocking is permitted by providing adequate clearance between this stud and the aperture in the blocking plate through which it passes. This rockable mounting enables the blocking plates to seat snugly against the faces of the valves.

The means for exerting force upon the blocking plates

24 and 25 in order to block the valves 14 and 15 are as follows. The end of the casing 19 shown in Fig. 1 is closed by a cover 20 which comprises an inwardly-projecting hollow boss 21 the innermost end 22 of which constitutes the cylinder for the larger piston 23 hereinbefore referred to. The smaller piston 29 is fixed to the larger piston 23 by a bolt 30 threaded into a piston rod 31 which is slidably within an aperture 32 formed in an inwardly projecting boss 33 forming part of an annular member 34 fixed to the cover 20 by studs 35. The inner end part 36 of the boss 33 constitutes the cylinder for the smaller piston 29. The bolt 30 is centrally apertured, this aperture connecting with an aperture 37 in the bolt head.

A strong spring 38 is provided to urge the piston assembly 23, 29, 31 to the left in Fig. 1, thus exerting pressure through the head of the bolt 30 upon the bridge piece 27 and thus upon the two blocking plates 24 and 25.

The front face of the larger piston 23, that is the left face in Fig. 1, is always subjected to the pressure in the reservoir which is connected to the space within the cover 20. The rear face of this piston and the front face of the piston 29 are always at atmospheric pressure since the space within the hollow boss 21 is in communication with the atmosphere through a port 39. The space 70 into which the piston rod 31 extends is closed, but not hermetically, by a dust cover 71. The space 70 is therefore at about atmospheric pressure.

In the position shown in Fig. 1 the valves are blocked and the clearance space at the rear face of the smaller piston 29 is in communication with the reservoir through a supply port 40 in the member 31, and through the central aperture and the aperture 37 in the bolt 30. Assuming that the reservoir is initially at atmospheric pressure, the air pressures on the piston assembly 23, 29, 31 are balanced and the whole force exerted by the spring 38 urges the blocking plates 24 and 25 against the valve faces.

When the compressor is started, the pressure in the reservoir rises, since some air is delivered through the valves 24 and 25 even when they are blocked. The reservoir pressure acts upon the larger piston 23 in a sense opposing the spring 38 and acts upon the smaller piston 29 in a sense assisting the spring 38. In effect, therefore, (neglecting the effect of atmospheric pressure on the small area of the piston rod 31) the spring 38 is opposed by the reservoir pressure acting upon a piston area equal to the difference between the areas of the larger and smaller pistons. As the reservoir pressure rises, therefore, the blocking force exerted by the spring 38 and the air pressures is progressively reduced until a condition is reached when the piston assembly begins to move to the right in Fig. 1. A very small movement of the member 31 results in the supply port 40 moving out of communication with the clearance space at the rear face of the smaller piston 29 and in this clearance space being placed in communication with the atmosphere through a slot 41 in the member 31 and a port 42 in the boss 33. There is thus a sudden drop in the force tending to urge the piston assembly to the left in Fig. 1 with the result that the piston assembly "pops," or moves suddenly, into its extreme right position. The springs beneath the blocking plates 24 and 25 are then free to move these plates fully away from their blocking position into their un-blocking position, this movement being assisted by the flow of air through the valves.

A spring-loaded slipper valve 43 is provided to seal the supply port 40 when the piston assembly is in the fully unblocked condition, that is in the normal running condition, in order to avoid unnecessary leakage from the reservoir.

When the pressure in the reservoir falls, at a certain value of this pressure the piston assembly moves to the left in Fig. 1 until the clearance space at the rear of the piston 29 is cut off from the atmosphere and put into

communication with the reservoir through the supply port 40. When this happens what is called the "pop-open" point is reached and the assembly moves rapidly into the fully-blocking position.

It may be noted that the "pop-open" point is determined by the pressure acting upon an area equal to the difference between the areas of the larger and smaller pistons whereas the "pop-shut" point is determined by the pressure acting on the whole area of the larger piston. For this reason the "pop-open" point is at a higher pressure than the "pop-shut" point.

In one example the larger piston 23 has a diameter of 6.7" and the smaller 29 a diameter 3.7". The outlet area of each of the two delivery valves is 1.8" x 3.1" and 15 the blocking plates 24 and 25 overlap this by about $\frac{1}{6}$ " or more all round. The spring has a rate of about 1200 lb./inch, and the spring load in the blocked position is about 2100 lb. Thus its size and weight is much less than for the corresponding springs in known blocking 20 means for streamline valves.

In order to increase the effective area of the smaller piston 29, the space 70 may be hermetically sealed by the cover 71 and a hole may be provided between the space 70 and the clearance space behind the piston 29. The 25 same pressures then act upon the rear face of the smaller piston and the end of the piston rod 31. In this way the pressure of the "pop-open" can be somewhat increased.

In the arrangement described with reference to Figs. 1 and 2 the pressure behind the larger piston 23, that is 30 the pressure within the hollow boss 21, is maintained at atmospheric and the pressure behind the smaller piston 29 is varied between reservoir pressure and atmospheric pressure. The reverse arrangement may, however, be used. Some means are then provided to vent 35 the clearance space behind the smaller piston 29 (and if desired also the space 70) to atmosphere and suitable ports operated by the movements of the piston assembly serve to connect the space within the boss 21 either to reservoir pressure or to atmosphere. The port 39 is of 40 course not provided.

Fig. 3 shows schematically a servo-valve control for a blocking piston. The separation of the control means from the compressor in this embodiment avoids any 45 risk of the control means becoming fouled or overheated by their proximity to the engine.

In Fig. 3, a compressor piston 45 is shown in the compressor cylinder 10 which communicates through delivery valves 14 and 15 with the interior of a casing 19 communicating with a reservoir 46. A blocking piston 50 50 operates in a cylinder formed within the casing 19. In order to block the valves 14 and 15 springs 48 urge the piston 47 to the left and cause projections 49 to engage suitable blocking plates (not shown) over the valves 14 and 15.

The control means comprise a cylinder 50 in which operates a piston 51 carrying a slide valve 52. The piston 51 is urged toward the left by a spring 53 and is shown in its left-most position corresponding to full blocking of the valves 14 and 15. The clearance space 54 over the piston 51 is connected by a pipe 55 with the reservoir 46 and the space behind the piston 47 is connected by a pipe 56 with ducts 57 and 58 in a member 59 co-operating with the slide valve 52. A port 60 in the slide valve 52 communicates through an aperture in the piston 51, space 54, and pipe 55 with the reservoir 46. A port 61 in the slide valve 52 is in communication with the atmosphere. A smaller piston 62 connected to the larger piston 51 operates in a cylinder 63 and the clearance space 64 behind the smaller piston communicates through a 65 duct 65 with the duct 57. The clearance space 66 behind the larger piston 51 is connected to the atmosphere through a port 67.

When the compressor is started the reservoir pressure rises and this pressure in the space 54 acts against the spring 53. The reservoir pressure also acts through the 75

port 60 and the duct 65 upon the rear face of the smaller piston 62. Thus, as in the embodiment of Figs. 1 and 2, the reservoir pressure acts in effect upon an area equal to the difference between the areas of the larger and smaller pistons 51 and 62 in opposition to the spring 53.

In addition, the reservoir pressure acts through the duct 57 and the pipe 56 upon the rear face of the piston 47 so that in the condition being considered equal pressures act upon the two sides of the piston 47 and the whole force exerted by the spring 48 is applied to block the valves 14 and 15.

At a predetermined value of the reservoir pressure, the slide valve 52 moves to the right sufficiently to disconnect the duct 57 from the port 60 and shortly afterwards connects the duct 58 with the port 61 and therefore to the atmosphere. The piston assembly 51, 62 with the slide valve 52 then "pop" into their un-blocking position and the whole reservoir pressure is suddenly brought to act upon the front face of the piston 47 against the spring 48, thus unblocking the valves 14 and 15.

I claim:

1. A free-piston air compressor comprising a compressor cylinder, a compressor piston operating in said cylinder, an air reservoir, a passage connecting said cylinder to said reservoir, at least one delivery valve in said connecting passage, means for blocking said delivery valve, means for exerting force upon said blocking means to urge said blocking means into their blocked position, and blocking control means for controlling the application of said force, said blocking control means comprising two control cylinders of different diameters, a control piston operating in each control cylinder, said control pistons being coupled together and being movable in said control cylinders between a blocked and an un-blocked position, spring means urging said control pistons toward their blocked position, means connecting the front face of the larger control piston to said reservoir, pressure on this face opposing said spring means, means connecting the rear face of one of said control pistons to the atmosphere, and means operated

by displacement of said control pistons to connect the rear face of the other of said control pistons to said reservoir in the blocked position of said control pistons and to connect the rear face of said other piston to the atmosphere in the un-blocked position of said control pistons, pressure on the rear face of said other piston assisting said spring means.

2. A free-piston air compressor comprising a compressor cylinder, a compressor piston operating in said cylinder, an air reservoir, a passage connecting said cylinder to said reservoir, at least one delivery valve in said connecting passage, means for blocking said delivery valve, means for exerting force upon said blocking means to urge said blocking means into their blocked position, and blocking control means for controlling the application of said force, said blocking control means comprising two control cylinders of different diameters, a control piston operating in each control cylinder, said control pistons being coupled together and being movable in said control cylinders between a blocked and an un-blocked position, spring means urging said control pistons toward their blocked position, means connecting the front face of the larger control piston to said reservoir, pressure on this face opposing said spring means, means connecting the rear face of the larger control piston to the atmosphere, and means operated by displacement of said control pistons to connect the rear face of the smaller control piston to said reservoir in the blocked position of said control pistons and to connect the rear face of said smaller piston to the atmosphere in the un-blocked position of said control pistons, pressure on the rear face of said smaller piston assisting said spring means.

3. A free-piston air-compressor according to claim 2, wherein the last-named means comprise ports operated by displacement of said control pistons.

4. A free-piston air-compressor according to claim 2, wherein said spring means exert force upon said blocking means.
